UNITED STATES PATENT OFFICE

THOMAS H. BETTY, OF MANCHESTER, VIRGINIA.

DESIGN FOR A CHURN-BODY AND SUPPORT.

SPECIFICATION forming part of Design No. 28,875, dated June 14, 1898.

Application filed October 30, 1896. Serial No. 610,638. Term of patent 7 years.

To all whom it may concern:

Be it known that I, THOMAS H. BETTY, a citizen of the United States, residing at Manchester, in the county of Chesterfield and State 5 of Virginia, have invented and produced a new and original Design for a Churn-Body and Support, of which the following is a specification.

My invention relates to a design for a churn-
10 body and support.

In the accompanying drawings, Figure 1 is a view of a churn-body and support embodying my design, and Fig. 2 is a side elevation thereof.

15 The leading features constituting my design consist in the peculiar churn-body and the A-shaped support for said churn-body.

The base or support of the churn-body comprises inclined legs 1, parallel cross-bars 2,

and a bar 3, connecting said cross-bars. It 20 will be observed that the inclined legs and the bar 3 when viewed from the side of the churn-body present to the eye the form of the letter A. The body consists of the side boards 5, curved ends 6, top 7, and handles 8. The 25 ends of said side boards 5 are finished with compound curves 9, and the lower or bottom edge of said sides is curved so as to present a rocker-like finish 10.

I claim—

30 The design for a churn-body and support, substantially as shown and described.

In testimony whereof I affix my signature in presence of two witnesses.

THOMAS H. BETTY.

Witnesses:

AUGUSTINE ROYALL,
CLARENCE VADEN.
